UNITED STATES PATENT OFFICE

IRVING F. WEBB, OF ELIZABETH, NEW JERSEY, ASSIGNOR TO THE SINGER MANUFACTURING COMPANY, OF ELIZABETH, NEW JERSEY, A CORPORATION OF NEW JERSEY

WORKTABLE

Application filed July 30, 1932. Serial No. 626,528.

This invention relates to improvements in work-tables, such as power-tables, cutting-tables and the like, and has for its object to provide simplified means for securing the 5 table-top or top-boards upon supporting standards, and more particularly for securing abutting sections of said top-boards upon the standards.

The invention consists in the devices, combinations and arrangement of parts herein- 10 after described and claimed.

This application is, in part, a continuation of my prior patent application Serial No. 614,918, filed June 2, 1932.

15 In the accompanying drawing, Fig. 1 is a front side elevation, partly in section, of a portion of a work-table having top-boards secured by an improved top-board clamping device. Fig. 2 is an end view of a portion 20 of the cutting-table. Fig. 3 is a side elevation, partly in section, of a modified arrangement for clamping the top-boards of a table upon a supporting standard.

25 As represented in the drawing, the cutting-table has a table-top supporting structure including vertically adjustable legs 1 and 2 constituting standards supporting channel-bar rails 3 and 4 which, in the preferred embodiment of the invention, are of 30 inverted U-shape and are disposed crosswise of top-boards 5 and 6. The top-board 5 is an end board of the table, overlying the end rail 3 and resting upon a portion of the intermediate rail 4 which also supports one 35 end of the top-board 6 in abutting relation with the end-board 5. The other extremity of the top-board 6 may overlie an end rail in a manner similar to the overlying relation of the board 5 with respect to the rail 4, to thereby constitute an end-board, or it 40 may be disposed in abutting relation with still another top-board, dependent upon the desired length of the table.

45 Referring more particularly to Figs. 1 and 2 of the drawing, to the under face of the top-board 5 at opposite sides of the end-rail 3, and to the under faces of the abutting extremities of the top-boards 5 and 6 at opposite sides of the intermediate rail 4, are secured substantially U-shaped angle-

brackets by screws, as 7, passing through apertures in the oppositely directed feet 8 of each of said brackets. The bottom member 9 of each of said brackets is preferably slightly inclined upwardly toward the adjacent table-rail, and is apertured to receive a bolt 10 threaded into a nut 11 confined between the side-members 12 of the bracket against rotation. The bolts 10 directly adjacent opposite sides of a rail are convergently inclined downwardly to engage the rail therebetween at the lower edges of the rail, said bolts passing through suitable apertures provided directly below the lower edges of the rail in a channeled clamp-member 13 having upturned side flanges held by the bolt-heads 14 against the lower edges of the rail. Each clamp-member 13 is bent upwardly between its ends to provide bolt-engaged portions extending beyond the outer sides of the rail at a downward inclination and in substantially parallel relation with the bottom-members 9 of the respective angle-brackets connected therewith. Preferably lock-washers 15 are interposed 55 between the bolt-heads 14 and the clamp-members to guard against inadvertent loosening of the bolts.

The described construction constitutes a 60 very powerful table-top clamping expedient, whereby the adjacent extremities of the boards 5 and 6 may not only be drawn downwardly upon the rail 4, but also drawn toward each other into closely abutting relation. In fact, the described expedient provides for straightening warped top-boards, 65 and is therefore also useful for securing the extremity of a board overlying an end rail 3. Nevertheless, the device is of simple construction, may be manufactured at low cost 70 and provides for ready shipment and installation of a table equipment.

In the modification illustrated in Fig. 3 of the drawing, angle-plates 16 are secured by screws 17 to the under faces of the top-boards 75 5 and 6, near the adjacent extremities of said top-boards and at opposite sides of the rail 4, said angle-plates 16 having depending members 18 preferably convergently inclined downwardly. The members 18 are 80

each apertured to receive the hooked upper extremity of a turn-buckle section 19 threaded into a collar 20 adjustably connecting said section 19 with a similar section 21 of which the lower end is correspondingly hooked. The hooked ends of the turn-buckle sections 21 enter suitable apertures provided in a channeled clamp-member 22 having turned up side flanges 23 which are 10 suitably recessed to receive the lower edges of the rail 4. As in the case of the bolts 10, by tightening the downwardly-converging turn-buckles the adjacent extremities of the table-top boards are not only firmly secured 15 upon the rail 4, but are also drawn into closely abutting relation.

Having thus set forth the nature of the invention, what I claim herein is:—

1. A work-table having a supporting structure including a table-top supporting rail, a table-top overlying said rail, a clamp-plate restrained by said rail against movement toward the table-top, and downwardly-converging securing devices disposed at opposite sides of said rail connecting said table-top and clamp-plate.

2. A work-table having a supporting structure including a table-top supporting rail of inverted U-shape, a table-top overlying said rail, a clamp-plate disposed in engagement with the lower edges of said rail, and adjustable table-top securing devices disposed at opposite sides of said rail connecting said table-top and clamp-plate.

3. A work-table having a supporting structure including a table-top supporting rail, a table-top overlying said rail, a clamp-member in engagement with the underside of said rail, and downwardly-converging securing devices connecting said table-top and clamp-member, said devices engaging the outer sides of said rail at the lower edges thereof.

4. A work-table having a supporting structure including a table-top supporting rail of inverted U-shape, a table-top overlying said rail, a clamp-member in engagement with the lower edges of said rail and extending outwardly beyond said rail at a 50 downward inclination, and downwardly-converging securing devices connecting said table-top and clamp-member, said devices engaging the outer sides of said rail at the lower edges thereof.

5. A work-table having a supporting structure including a table-top supporting rail of inverted U-shape, a table-top overlying said rail, brackets fixed to the under face of said table-top at opposite sides of 60 said rail, a clamp-member in engagement with the lower edges of said rail, and downwardly-converging bolts disposed at opposite sides of said rail and connecting said brackets and clamp-member.

6. A work-table having a supporting

structure including a table-top supporting rail of inverted U-shape, a table-top overlying said rail, brackets fixed to the under face of said table-top at opposite sides of said rail, a channeled clamp-member having upturned side flanges disposed crosswise of and in engagement with the lower edges of said rail, and adjustable table-top securing devices disposed at opposite sides of said rail connecting said table-top and clamp-member.

7. A work-table having a supporting structure including a table-top supporting rail of inverted U-shape, a table-top overlying said rail, brackets fixed to the under face of said table-top at opposite sides of said rail, a clamp-member in engagement with the lower edges of said rail and projecting outwardly beyond said rail at a downward inclination, and downwardly-converging bolts disposed at opposite sides of said rail and connecting said brackets and clamp-member.

8. A work-table having a supporting structure including a table-top supporting rail of inverted U-shape, a table-top overlying said rail, brackets fixed to the under face of said table-top at opposite sides of said rail, a channeled clamp-member having upturned side flanges disposed crosswise of and in engagement with the lower edges of said rail, said clamp-member being bent upwardly between the sides of the rail to project outwardly beyond opposite sides of the rail at a downward inclination, and downwardly-converging bolts disposed at opposite sides of said rail and connecting said brackets and clamp-member.

9. A work-table having a supporting structure including a table-top supporting rail, a table-top overlying said rail, bracket-members fixed to the under face of said table-top at opposite sides of said rail, a clamp-member projecting beyond opposite sides of said rail and restrained by the rail against movement toward the table-top, downwardly-converging bolts disposed at opposite sides of said rail and connecting said bracket and clamp members, said bolts having heads engaging the under side of said clamp-member, and securing nuts for said bolts restrained against rotation by said bracket members.

10. A work-table having a supporting structure including a table-top supporting rail of inverted U-shape, a table-top overlying said rail, a clamp-member disposed in engagement with the lower edges of said rail, and downwardly-converging securing devices disposed at opposite sides of said rail connecting said table-top and clamp-member, said securing devices engaging said clamp-member at points directly below the lower edges of said rail.

11. A work-table having a supporting

structure including a table-top supporting rail, a table-top overlying said rail, plates fixed upon the under face of said table-top at opposite sides of said rail, and downwardly-converging turn-buckles connecting said plates with said rail for fixedly securing said table-top upon the rail.

12. A work-table having a supporting structure including a table-top supporting rail, a table-top overlying said rail, angle-plates fixed upon the under face of said table-top having depending members disposed at opposite sides of said rail, a clamp-plate restrained by said rail against movement toward the table-top, and turn-buckles

connecting said clamp-plates with the depending members of said angle-plates.

13. A work-table having a supporting structure including a top-board supporting rail of inverted U-shape, top-boards having abutting extremities disposed upon said rail, complementary angle-plates fixed upon the under faces of said top-boards having depending members disposed at opposite sides of said rail, a clamp-plate disposed in engagement with the lower edges of said rail, and downwardly-converging turn-buckles connecting said clamp-plate with the depending members of said angle-plates.
